UNITED STATES PATENT OFFICE.

GEORGE S. HOLMES, OF LIVERPOOL, ENGLAND.

CAR-COUPLING.

SPECIFICATION forming part of Letters Patent No. 690,954, dated January 14, 1902.

Application filed June 4, 1900. Renewed June 10, 1901. Serial No. 64,027. (No model.)

To all whom it may concern:

Be it known that I, GEORGE SOCKET HOLMES, a subject of the Queen of Great Britain and Ireland, and a resident of Liverpool, England, (whose post-office address is 312 Kensington, Liverpool, England,) have invented a certain new and useful Wagon-Coupling, (for which I have applied for patents in Great Britain, No. 5,782, dated March 28, 1900, and No. 8,539, dated May 9, 1900,) of which the following is a specification.

This invention relates to railway-vehicle couplings which are partially automatic in their action.

Reference being had to the drawings, Figure 1 is a side view, and Fig. 2 is a plan, of a coupling arranged according to my invention. Figs. 3, 4, 5, and 6 are detail views showing parts of the mechanism separately. Fig. 7 is a side view, and Fig. 8 is a plan, of a modified form of my invention.

The coupling *a* (shown in Figs. 1 and 2) is of the ordinary three-link type. Pivoted to a spindle *b*, disposed across the wagon end and provided with operating-levers, is a lifting-arm *c*. This arm is shown more clearly in Figs. 3 and 4 and comprises two portions—namely, the cradle *d*, which supports the outer link of the coupling, and the tubular portion *c*, into which such cradle telescopes when it comes in contact with any obstruction. The cradle *d* has a specially-formed jaw *e*, adapted to receive the outer link, and is extended by the springs *f* in the tubular part *c*. The lifter *c* is pivoted at *g* to the spindle *b*, whereby it may move to right or left, and so place the coupling on the hook of the next wagon, even when the two wagons are standing on a curved track, and this right or left movement is effected by the draw-rod *h*, which is shown more clearly in Fig. 5. Projecting from the rod *h* is a plate *i*, which engages a pin *j* on the lifter *c*. A handle is formed on each end of the rod *h*, whereby it may be pulled, and so the lifter and coupling are rocked to one side or the other. The rod *h* is carried in guides attached to the spindle *b*.

Keyed on the spindle *b* is a gapped disk *k*. (Shown separately in Fig. 6.) This disk 50 is engaged by a spring-actuated detent *l*, which retains the coupling in the raised position assumed in Fig. 1—namely, in position for engagement with the hook of the next wagon. This detent is withdrawn from engagement with the disk *k* automatically on impact of the two wagons by means of the inclined plane *m* on the rod *n*, the bell-crank levers *o*, and the bars *p*, which latter are disposed in rear of the buffers *q*. The return 60 action of these parts is due to the spring *r*. The rod *n* is provided with handles, whereby the detent may be withdrawn by hand. The disk *k* possesses two gaps, one being engaged by the detent *l* when in the raised position 65 above referred to, the other gap being engaged when the lifter *c* is lowered and out of use.

In Figs. 7 and 8 a two-part shackle-coupling is shown operated by a lifting-arm *c*, projecting from a spindle *b*, on which is keyed the gapped disk *k*. The disk *k* is engaged by the detent *l* and is released in the manner described with reference to Figs. 1 and 2.

Having now described my invention, what 75 I claim as new, and desire to secure by Letters Patent, is—

1. In combination, the lifter *c* pivoted to its operating-spindle *b*, the gapped disk *k* on the spindle *b*, and the detent *l* engaging such disk and arranged to be withdrawn from such engagement by the inclined plane *m*, rod *n*, levers *o*, and bars *p* on impact of the buffers *q*, as described.

2. The combination with the lifter-operating spindle *b*, of the gapped disk *k* keyed thereon and engaged by the detent *l*, and means such as the inclined plane *m* and rod *n* for withdrawing such detent and releasing the lifter, substantially as described. 85 90

In witness whereof I have hereunto set my hand in presence of two witnesses.

G. S. HOLMES.
